UNITED STATES PATENT OFFICE.

RICHARD WEBB BURNETT, OF MONTREAL, QUEBEC, CANADA, ASSIGNOR OF ONE-HALF
TO HENRY H. VAUGHAN, OF WEMOUNT, QUEBEC, CANADA.

STEEL CAR.

1,250,136.

Specification of Letters Patent. Patented Dec. 18, 1917.

Application filed November 22, 1913, Serial No. 802,481. Renewed March 23, 1916. Serial No. 86,280.

To all whom it may concern:

Be it known that I, RICHARD WEBB BURNETT, a resident of the city of Montreal, in the Province of Quebec, Canada, a citizen of the United States of America, have invented certain new and useful Improvements in Steel Cars; and I do hereby declare that the following is a full, clear, and exact description of the same.

10 This invention relates particularly to single sheath steel box cars usually employed in the transportation of freight; and it has for its object to so construct a car of this type that it will possess maximum strength 15 with minimum amount of braces and other parts which usually increase the weight and cost of construction and maintenance.

To this end the invention may be said briefly to consist of a box car the sides of 20 which consist of single sheath steel vertically corrugated and having its corrugations tapered off a short distance from the top and bottom edges thereof, the top edges of the sheets being secured to the side plates, 25 and the bottom edges rigidly connected to the side members of the car floor, the side edges of each sheet being secured to the inner sides of posts of channel cross-section and reinforced at their lower ends by plates 30 extending across the outer sides of the posts and secured to the sheets at each side of each post. This construction is applied to the intermediate posts only, the corner posts of the car being inwardly facing angle-irons 35 between which and the side members of the car floor the contiguous side edges of the side sheets are secured and the door posts are outwardly facing angle-irons. The corner edges of the end sheets are also connected to the inside of angle-iron corner 40 posts.

For full comprehension, however, of my invention reference must be had to the accompanying drawings forming a part of 45 this specification, in which similar reference characters indicate the same parts, and wherein:

Figure 1 is a side elevation of one half of my improved car;

50 Fig. 2 is an end elevation illustrating one corner partly in vertical sectional view;

Fig. 3 is a horizontal sectional view taken on line S S Fig. 1;

Fig. 4 is an enlarged horizontal sectional 55 view of one of the posts and the manner of

connecting the side edges of the side plates thereto;

Fig. 5 is an enlarged detail sectional view of one of the corner posts illustrating the manner of connecting the side and end 60 sheets thereto;

Fig. 6 is a similar view of one of the door posts illustrating the manner of connecting the side sheet thereto; and

Fig. 7 is a vertical sectional view taken 65 on line X X Fig. 3 illustrating particularly the manner of uniting the end sheets to the car frame.

The side sheets of my improved car are indicated at *b* and the end sheets at *c*, each 70 of these sheets being vertically corrugated as at *b'* and *c'* and the corrugation being of the nature of embossments and extending from within a short distance of their lower edges to within a short distance of 75 their upper edges and of relatively large dimensions, five being usually sufficient for the side sheets and three between the posts stiffening the end sheets, the sheet portions between the corrugations being flat and of 80 even continuity with the top, bottom and side edges thereof. At the corners of the car the side edges are riveted to the inside of one of the flanges *d* of angle iron posts the other flange *e* of which has the contiguous 85 side edge of the end sheet riveted thereto this angle iron post being in turn riveted as at *f* to the channel side sill *g* of the car floor and riveted as at *g'* to the end sill while its upper end is rigidly secured by 90 rivets *m'* to a side plate *m* of Z-cross-section.

The door posts indicated at *k* are in the form of angle irons having one flange facing outwardly and the other flange riveted 95 at its lower end to the side sill *g*, the upper end of these door posts being secured to the side plate *m* by angle bracket *o* riveted to such side plate and the outwardly extending flange of the door post. The posts *p* between the corner and the door are in the form of channel irons riveted as at *p'* to the side sill *g* with their flanges facing outwardly, the side edges of the sheets being overlapped behind these posts and riveted as at *q* to the webs thereof, and the upper edges of the sheets are riveted as at *m'* to the inside of the side plate *m*.

The lower portions of the car sides thus 100 constructed and particularly the side posts 110

thereof are reinforced by relatively heavy plates *s* bent over the lower ends of the channel iron posts and extending for a short distance up the same and riveted at their 5 side edges to the sheets. This compensates for the absence of the corrugations at the lower edges of the sheets.

The corrugations contribute sufficient strength to the car and sides and ends to 10 permit the use of relatively light intermediate posts, the absence of the corrugations at the lower edges of the sheets being compensated for as above mentioned by the plates *s*.

15 What I claim is as follows:—

1. In a steel box car the combination with side sills and side plates, of corner posts and intermediate posts, vertically corrugated steel sheets secured at their side edges to the 20 corner posts and intermediate posts and the corrugations being less in length than the height of the sheets and such sheets being secured at their lower edges to the side sills and their upper edges to the side plates, 25 and means reinforcing the portion of the said structure contiguous to and including the lower ends of the intermediate posts, for the purpose of compensating for the absence of corrugations.

30 2. In a steel box car the combination with side sills and side plates, of corner posts and intermediate posts, the latter being of channel cross-section with outwardly facing flanges, vertically corrugated steel sheets secured at their side edges to the corner posts and inner sides of the intermediate posts and the corrugations being less in length than the height of the sheets and such sheets being secured at their lower edges to the side 35 sills and their upper edges to the side plates and means reinforcing the portion of the said structure contiguous to and including the lower ends of the intermediate posts, for the purpose of compensating for the absence 40 of corrugations.

45 3. In a steel box car the combination with side sills and side plates, of corner posts and intermediate posts, the latter being of channel cross-section with outwardly facing flanges, vertically corrugated steel sheets secured at their side edges to the corner posts 50

and inner sides of the intermediate posts and the corrugations being less in length than the height of the sheets being secured at their lower edges to the side sills and their upper edges to the side plates, reinforcement plates engaging the lower portions of the intermediate posts and secured in place reinforcing the portion of the said structure contiguous to the posts, for the purpose of compensating for the absence of corrugations. 55

4. In a steel box car the combination with side members of the floor and roof members of corner posts and intermediate posts, the latter being of channel cross-section with 60 outwardly facing flanges, vertically corrugated steel sheets secured at their side edges to the corner posts and inner sides of the intermediate posts and the corrugations being less in length than the height of the 65 sheets and such sheets being secured at their lower edges to the side floor members and their upper edges to the roof members, reinforcement plates extending over the lower portions of the intermediate posts and secured at their side edges to the sheets, for the purpose of compensating for the absence 70 of corrugations. 75

5. In a steel box car the combination with side members of the floor and roof members of corner posts and intermediate posts, the latter being of channel cross-section with 80 outwardly facing flanges, vertically corrugated steel sheets secured at their side edges to the corner posts and inner sides of the intermediate posts and the corrugations being less in length than the height of the sheets and such sheets being secured at their lower edges to the side floor members and their upper edges to the roof members, 85 relatively thick reinforcement plates engaging the lower portions of the intermediate posts and secured at their side edges to the sheets, for the purpose of compensating for the absence 90 of corrugations. 95

In testimony whereof I have signed my name to this specification in the presence of two witnesses.

RICHARD WEBB BURNETT.
